UNITED STATES PATENT OFFICE.

WILBUR S. UPSON, OF MANSFIELD, OHIO.

COMBINED NUT AND PIPE WRENCH.

1,212,287.

Specification of Lettefs Patent. Patented Jan. 16, 1917.

Application filed September 12, 1916. Serial No. 119,749.

To all whom it may concern:

Be it known that I, WILBUR S. UPSON, a citizen of the United States of America, residing at Mansfield, in the county of Rich-
5 land and State of Ohio, have invented cer-
tain new and useful Improvements in Com-
bined Nut and Pipe Wrenches, of which
the following is a specification.

This invention relates to a combined pipe
10 and nut wrench.

The primary object of this invention con-
sists in providing a wrench with a reversi-
ble and separable movable jaw to permit it
to be used for a pipe or nut wrench.

15 A further object is to provide means of
mounting a worm cog screw upon the sta-
tionary part or head of the wrench whereby
the worm cog screw is normally, but, yield-
ingly maintained in engagement with the
20 cog teeth formed in the shoe of the move-
able jaw which permits the worm cog screw
to be withdrawn from engagement with the
cog teeth at the will of the user to afford
facilities for quick and rapid adjustment
25 of the movable jaw with respect to the sta-
tionary jaw.

A further object of this invention con-
sists in forming a guideway in the head and
stationary jaw of the wrench which inter-
30 sects with a right angularly related aper-
ture having a worm cog screw arranged
therein, and which is adapted to engage the
cog teeth of the movable jaw to impart
movement thereto, said movable jaw
35 fitted to the guideway in such a manner as
to permit its withdrawal and reversal from
the guideway, in order to present a face
suitable for manipulating pipes or a face
suitable for manipulating nuts as desired
40 by the user.

A further object is to pivotally secure a
worm cog screw on the head of a wrench
in such a manner as to permit it to coöper-
45 ate with cog teeth formed in a movable
jaw, the worm cog screw being arranged
to be pivoted to insure proper mesh of the
cog teeth and worm cog screw at all times
when it is being manipulated for the pur-
pose intended.

50 These and other objects are attained by
the construction of the wrench as illustrated
in the accompanying drawing in which:—

Figure 1 is a side elevation of a wrench
partly in section, showing my invention ap-
55 plied to a side jaw wrench, the cog teeth
of the movable jaw and worm cog screw be-

ing shown in mesh. Fig. 2 is a side eleva-
tion of a side jaw wrench showing the in-
vention applied thereto. The worm cog
screw being shown disengaged from the cog 60
teeth of the movable jaw. Fig. 3 is a side
elevation showing a modified form of the
invention, the worm cog screw being ar-
ranged to be permanently engaged with the
cog teeth of the shoe. Fig. 4 is a section 65
on the line 4—4 of Fig. 3.

In the drawing reference numeral 1 repre-
sents the head, 2 the stationary jaw, and
3 the handle of the wrench. The head is
provided with a guideway 4 to slidably re- 70
ceive a shoe 5, which is attached or made
integral with a movable jaw 6. An open-
ing 7 is formed in the head in right angular
relation to the guideway and communicates
therewith. One of the walls of the open- 75
ing 7 is preferably provided with a slot 8
to receive one end of a spindle 9 which is
pivoted to a pin 10, thereby permitting the
spindle to be oscillated from the axis of the
pin, but preventing it from moving in any 80
other direction.

A worm cog screw 11 is mounted upon
the free end 9 of the spindle for rotation
and it is adapted to be normally forced into
mesh with the cog teeth 12 formed in the 85
shoe by a coil spring 13, which is com-
pressed in a suitable aperture, leaving one
end exerting a tension against the spindle
in close proximity to the pin 10. The move-
able jaw 6 is provided with two faces, one 90
face 14 is formed flat for use in manipulat-
ing nuts and the like, and the other face
is inclined and provided with a series of
teeth 15 for use in manipulating pipes or
the like. 95

In the type shown in Fig. 3 the spindle
9 is provided with a threaded end which
engages a threaded aperture in one of the
walls surrounding the aperture 7, the worm
cog screw being constantly maintained in 100
mesh with the cog teeth as the spindle 9
has no pivoted radial movement from the
axis of the pin 10. When it is desired to re-
verse the movable jaw to use it either for
a pipe wrench or a nut wrench, the worm 105
screw is manipulated until the cog teeth of
the shoe are disengaged therefrom, and the
movable jaw is then withdrawn from the
guideway and again inserted in the guide-
way thereby presenting the desired face to 110
the work.

Attention is called to the fact that the

structure described provides a combined pipe and nut wrench requiring no additional parts, or attachment, to perform both functions. In the type shown in Figs. 1 and 5 2 the adjustment of the movable jaw can be accomplished rapidly by forcing the worm cog screw against the tension of the spring 13, thereby disengaging the worm cog screw from the cog teeth of the shoe. Applicant 10 is aware that the art discloses a worm cog screw engaging cog teeth formed in the shoe of a movable jaw, therefore, said construction is not claimed broadly, but applicant does claim the means shown for quickly and 15 rapidly adjusting the movable jaw with respect to the stationary jaw and the arrangement of reversing the movable and separable jaw and its operating mechanism as specifically pointed out and defined in the 20 claims appended hereto.

Attention is called to the fact that the spring in exerting a pressure upon the spindle performs a dual function, that is, it 25 yieldingly forces the worm cog screw to mesh with the cog teeth, and it at the same time forces and keeps the worm cog screw and cog teeth constantly in frictional contact with each other, thereby preventing the 30 worm cog screw from turning and changing the adjustment of the movable jaw.

I claim:

1. In a wrench provided with a stationary jaw, an integral head and handle, said head having a guideway formed therein and 35 an angularly related aperture crossing said guideway and communicating therewith, a pin secured to said head, a spindle pivotally secured for oscillation to said pin, a worm cog screw loosely mounted on said spindle, 40 in combination with a double-faced movable, separable and reversible jaw having a shoe provided with cog teeth, said shoe being adapted to be inserted in the guideway to slidably engage the guideway and mesh 45 with the worm cog screw, and yielding means arranged between the pin and worm

screw which is adapted to exert a pressure on the spindle to normally maintain the worm cog screw in mesh with the cog teeth of the movable jaw.

2. In a wrench provided with a stationary jaw, an integral head and handle, said head having a guideway formed therein and an angularly related aperture crossing said guideway and which communicates therewith, a pin secured to said head, a spindle pivotally secured for oscillation to said pin, a worm cog screw loosely mounted on said spindle, in combination with a double-faced movable, separable and reversible jaw having a shoe provided with cog teeth, said shoe being adapted to be inserted in the guideway and mesh with the worm cog screw, and yielding means arranged between the pin and worm 60 screw which is adapted to exert a pressure on the spindle to normally maintain the worm cog screw in mesh with the cog teeth of the movable jaw.

3. In a wrench comprising an integral 70 stationary jaw head and handle, said head being provided with an open guideway and an angularly related opening which crosses said guideway and communicates therewith, a pin secured to said head, a spindle having 75 one end fitted within a slot formed in one of the walls surrounding said opening which is pivotally secured for oscillation to said pin, a worm cog screw mounted for rotation on the free end of said spindle, in combination 80 with a double-faced movable, separable and reversible jaw provided with a series of cog teeth, and which can be slidably inserted in said guideway to engage the worm cog screw, and yielding means arranged between 85 the pin and worm screw which is adapted to exert a pressure on the spindle to normally maintain the worm cog screw in mesh with the cog teeth of the movable jaw.

In testimony whereof I affix my signature.

WILBUR S. UPSON.
